UNITED STATES PATENT OFFICE.

JOHN G. MACCUNE, OF MINNEAPOLIS, MINNESOTA, ASSIGNOR OF ONE-HALF TO FRANK H. PETERSON, OF MINNEAPOLIS, MINNESOTA.

EMBROIDERY-HOOP.

1,088,913.

Specification of Letters Patent.

Patented Mar. 3, 1914.

Application filed September 16, 1912. Serial No. 720,514.

To all whom it may concern:

Be it known that I, JOHN G. MACCUNE, of Minneapolis, Hennepin county, Minnesota, have invented certain new and useful 5 Improvements in Embroidery-Hoops, of which the following is a specification.

In embroidery hoops as usually constructed the spring device provided in connection with one of the rings for causing it to grip 10 the cloth to be embroidered frequently becomes weakened so that the rings, instead of fitting snugly together, will be loose and will not grip the cloth securely.

The object of my invention is to entirely 15 obviate this objection in an embroidery hoop and provide a construction which at all times will cause the cloth to be securely gripped and firmly held.

A further object is to provide an embroidery 20 hoop of simple construction and one which can be easily operated.

In the accompanying drawings forming part of this specification, Figure 1 is a sectional view of an embroidery hoop embodying my invention, on the line $x-x$ of Fig. 2, Fig. 2 is an edge view of the same, showing the rings partially separated from one another preparatory to the insertion of the cloth between them. Fig. 3 is a sectional view, showing a reversal of the construction illustrated in Figs. 1 and 2, on the line $y-y$ of Fig. 4, Fig. 4 is a sectional view through the hoop shown in Fig. 3, showing the rings partially separated, Fig. 5 is a plan view 30 showing a construction in which the spring is omitted, the cloth being gripped by the tension of the rings upon one another, Fig. 6 is a sectional view of the same.

In the drawing, 2 represents the outer 40 ring, cut transversely at 3 and having an annular groove or depression 4 formed therein to receive a spring device 5. A second ring 6 is provided, adapted to fit within the ring 2 and having an annular groove 7 to receive the rib formed on the inner surface of the ring 2 by the pressing of the groove 4 therein. These rings may be made of any suitable material, preferably fiber, which on account of its toughness and durability and 50 comparative light weight forms a very suitable material for a device of this kind. The ring 6 is made of sufficient diameter to separate or spread the ends of the ring 2 and put the spring 5 under tension so that when 55 the cloth to be embroidered is placed over the

ring 6 and the ring and cloth thrust into the ring 2, the cloth will be securely clamped between the two rings and positively held against slipping during the embroidering operation. The spring 5 extends almost entirely around the ring 2 and supports and braces it at all points, and the strain on the spring is so evenly distributed throughout its length that it will not become weakened through use and will exert a steady, uniform 60 pressure on the outer ring and cause it to grip the cloth at all points of contact therewith.

In Figs. 3 and 4 the arrangement of the parts is reversed. The outer ring 8 is made 70 continuous and the inner ring 9 is cut transversely at 10 and provided on its inner surface with an annular groove or recess 11 to receive a spring 12, corresponding to the one described, and adapted to exert an outward 75 pressure to force the rib 13 into the annular groove 14 provided in the ring 8. The cloth to be embroidered will be inserted between the rings in the manner described with reference to Figs. 1 and 2 and the pressure of 80 the ring will be uniform at all points on the cloth.

In Figs. 5 and 6 I have illustrated another modification, which consists in providing an outer ring 15 having an annular rib 16 85 formed on its inner surface and cut transversely at 17. This transverse cut is irregularly formed, so that there will be no gap between the ends of the ring when the fabric is inserted between it and the inner ring. 90 The inner or second ring 18 is preferably provided with an internal annular groove 19 to receive the rib 16 but the ring, instead of being cut transversely, is continuous. These rings may be formed of fiber or of 95 wood having a sufficient degree of spring to grip the fabric when the cloth to be embroidered is inserted between the rings. I prefer, however, to use the construction in which the metallic circular spring is employed to clamp the split ring on the work, as the long bearing of this circular spring on the ring will produce a uniform pressure on the cloth and be far more durable than a coiled spring or similar device located at the 100 ends of the ring.

The device may be made in various sizes and various means may be employed for mounting the spring on the ring and still be within the scope of my invention. 110

I claim as my invention:—

1. An embroidery hoop comprising an inner continuous ring, an outer ring split or divided transversely and adapted to be expanded sufficiently to encircle said inner ring, said rings having annular grooves or depressions therein and a spring consisting of a metal hoop divided transversely at one point and adapted to encircle said rings and bear uniformly thereon and cause said rings to exert a uniform pressure on the cloth inserted between them.
2. An embroidery hoop comprising an inner and an outer ring, one of said rings being split or divided transversely and

adapted to grip the adjacent surface of the other ring, said rings having grooves or depressions therein and a spring hoop divided transversely at one point and fitting within one of said grooves and bearing uniformly on said rings and causing them to exert a uniform pressure on the cloth inserted between them.

In witness whereof, I have hereunto set my hand this 12th day of September, 1912. 25

JOHN G. MACCUNE.
